CLAIM

The ornamental design for a side panel for a vehicle, as shown and described.

DESCRIPTION

FIG. 1 is a left perspective view of a side panel for a vehicle according to the design;

FIG. 2 is a right perspective view thereof;

FIG. 3 is a front view thereof; and,

FIG. 4 is a right perspective view thereof showing a possible environment.

The stippling disclosed in FIGS. 1-3 represents a rough texture on the presented surfaces.

The broken lines shown illustrate portions of the side panel for a vehicle that form no part of the claimed design.
